GRINDING MACHINE

Alfred J. Bowen, Beloit, Wis.

Application November 23, 1949, Serial No. 129,149

23 Claims. (Cl. 51—131)

1

The present invention relates in general to grinding machines and more in particular to machines known as surface grinders and adapted to grind accurately finished surfaces on parts of various sizes and shapes such as may be held by suitable chucks or work holders during the grinding operation.

My improved grinding machine is characterized by a horizontal bed on which one or more work supports may be mounted, a vertical column extending upward from the bed, a master bearing member rotatably and slidably supported on the column and carrying in balanced relation a grinding wheel assembly on one side and a driving motor on the opposite side, and mechanism for raising and lowering the bearing member on the column in order to adjust the grinding wheel relative to the work.

The object of the invention is to provide a new and improved grinding machine of the foregoing type.

A special feature of the invention is an automatic control arrangement for performing a predetermined grinding cycle on a part held by a rotatable work support, the arrangement including an automatic feed for the grinding wheel and automatic latching and releasing mechanism for the grinding wheel assembly which maintains it in operative relation to the work during a grinding cycle and restores it to a non-interfering position at the end of the grinding cycle to enable the operator to remove the finished work piece and replace it with the next piece to be ground.

The foregoing and other features are described in detail hereinafter, reference being made to the accompanying drawings, in which—

Fig. 1 is a front elevation of a grinding machine embodying the invention, including a section through the base and certain other parts on the line 1—1—1, of Fig. 2, and a section through the rotatable work support on the line 1', Fig. 2;

Fig. 2 is a section on the line 2—2, Fig. 1, and is essentially a top or plan view of the machine;

Fig. 3 shows a cam which forms part of the automatic feed mechanism;

Fig. 4 is a section through the master bearing member on the line 4—4, Fig. 1;

Fig. 5 shows a latch mechanism which is part of the automatic control;

Fig. 6 is a partial section on an enlarged scale on the line 6—6, of Fig. 2;

Fig. 7 is a diagrammatic circuit drawing showing the electrical equipment and wiring thereof;

2

Fig. 8 is an enlarged view of the micrometer indicator and part of the micrometer dial; and

Fig. 9 is a view of the work rotating mechanism as seen from the right in Fig. 1.

- 5 Referring to the drawings, the reference character 10 indicates a circular base having an upwardly extending rim 11. The rim has an annular interior recess for receiving the large flanged ring 12, the two forming a reservoir for coolant. 10 An overflow pipe 13 serves to drain the coolant into a sump (not shown) in the subbase 14. The circulating system for coolant may be of known character and has been omitted in order not to complicate the drawings.
- 15 The subbase is preferably rectangular in horizontal section and rests on the floor or other support for the machine. It is flanged at the top where it supports the base 10. The base may be secured to the subbase by means of countersunk screws such as 15. The base and subbase may be iron or steel castings, and the former preferably has an accurately finished horizontal interior surface 16 on which work holding chucks or other devices may be mounted. A known form 20 of magnetic chuck 17 is shown in Fig. 2.
- 25 The base 10 has an opening at the center thereof, surrounded by an annular recess. The hollow vertical column 18 has a flange at the bottom which rests in this recess. The column is secured in position by screws such as 19 which 30 pass through the flange and are threaded into the base. The upper portion of the column 18 is somewhat reduced in diameter and has a finished exterior surface for reception of the master bearing member 20.

- 35 The bearing member 20 is seen in elevation in Fig. 1 and in horizontal section in Fig. 4. It comprises a casting having finished interior bearing surfaces engaging the exterior surface of the column 18. The inside diameter of the bearing member is enlarged for some distance about midway between its upper and lower ends to provide an annular space 21 which is packed with grease. The left hand wall of the bearing member is divided by a vertical slot 22, Fig. 4, which is filled by 40 a compressible strip 23 of wood or other suitable material to prevent the escape of grease. The vertical slot 22 is bridged by three cap screws such as 24 by means of which the bearing member may be adjusted to a very close fit on the column 18. These screws also afford means for taking up wear, if any occurs.

- 45 For the major portion of its length downward from the top the bearing member 20 is square in cross section. From a point just below the

lower cap screw 24, however, the bearing member is round, forming a shoulder indicated at 25, Fig. 1. The rounded portion of the bearing member is indicated at 26. The plate 27, seen also in Fig. 2, has an opening for the rounded part 26 of the bearing member and rests against the shoulder 25, where it is secured at the four corners of the bearing member by screws such as 29. The plate 27 extends to the right nearly as far as the inner wall of ring 12, where it supports the curved apron or guard 28. The handle 30 is provided for use by the operator in rotating the bearing member and parts supported thereby on the column 18, as will be explained herein-after.

The reference character 41 indicates a cylindrical guard which is secured to the rounded lower end 26 of the bearing member 20 by screws such as 42 and extends downward around the column 18 as shown.

The reference character 31 indicates a housing for the grinding wheel spindle and is shown, in Fig. 1, also in dotted lines in Fig. 2. The housing is rectangular in cross section and is provided with vertical flanges, such as 32 through which cap screws such as 33 extend to clamp the housing to the bearing member 20. The upper end of the housing is shown in section in Fig. 6, from which it will be seen that the housing is pivotally supported, before the screws 33 are tightened, on the stud 34, the base of which is fixed in a hole in the bearing member 20. The holes in the flanges 32 through which the screws 33 pass are slightly larger than the screws, which makes it possible to adjust the housing about the stud 34 as a pivot to align the grinding wheel spindle with the column 18.

The hollow spindle is indicated at 35, Fig. 6, and is rotatably mounted in a vertical channel 36 in housing 31 by means of the ball bearing 37 at the top and one or more ball bearings (not shown) at the lower end of channel 36. The channel is closed above bearing 37 by means of the grooved cap 38 and the flanged collar 39, the latter having a press fit on the spindle 35 and being rotatable therewith. The pulley 43 is suitably secured to the spindle 35 at its upper end. At the lower end the spindle carries the grinding wheel 44, which can be seen in Fig. 1. The grinding wheel is removably secured to the spindle in known manner, details of which are not shown since they form no part of the invention.

The grinding wheel 44 is enclosed in a protective guard 45 which is attached to the lower end of the member 46 which in turn is slidably mounted on the housing 31. The member 46 may be adjusted relative to the housing 31 by a rack and pinion arrangement operated by the handle 47 in order to raise the guard 45 as the grinding wheel 44 wears away. The details are not shown since they form no part of the invention. It will be noted that the plate 27 has an opening for the guard 45 and the grinding wheel 44.

The motor 50 is mounted on the bearing member 20 opposite the housing 31. The mounting arrangement comprises a plate 51, Fig. 4, to which the base of the motor is attached, and a bracket 52 which is suitably secured to the bearing member 20. The plate and bracket are provided with overlapping ears through which holes are drilled to receive the pivot rod 53. A pulley 54 is mounted on the motor shaft and is connected with the pulley 43 on the grinding wheel spindle by V belts 55 and 56. The belts are shown in dotted lines in Fig. 1 and also appear in Fig. 75

6. They pull the motor and mounting plate 51 toward the bearing member 20 and against a stop 57, comprising a stud 57 which is threaded into the bearing member. This stud affords means for adjusting the tension of the belts.

The mechanism for adjusting the bearing member 20 vertically on the column 18 includes the flanged nut 60 and the micrometer screw 61, shown in Fig. 6. The upper portion of the nut extends through a hole in the circular plate 62 which rests against the flange on the nut and is rigidly secured thereto by means of screws such as 63. The plate 62 is positioned in a recess at the top of the bearing member 20, where it is secured by screws such as 64. Thus the nut 60 is firmly attached to the bearing member 20.

The micrometer screw 61 is threaded in the nut 60, extending for some distance above and below the same in the position in which the parts are shown, and is provided with a thrust bearing 65 at its lower end. The bearing 65 is supported on the disc or ring 66, and the latter normally rests on the shoulder 67 of the interior wall of the hollow column 18. The shoulder is formed by an enlargement of the bore of the column which extends a short distance down from the top as shown. As will be explained presently, the disc 66 may be raised off the shoulder 67 (as it is shown in the drawing) and lowered thereto by means of the tubular member 68.

The micrometer screw 61 is rotated by means of the hand wheel 70, seen best in Fig. 2. The hand wheel has a rim of large diameter, which enables it to be reached easily by the operator, and a central hub 71 to which the rim is connected by spokes as shown. The hub 71 is secured to the top of the tubular member 72 which surrounds the upper portion of the micrometer screw 61 and is provided with a flange 73 at its lower end. The micrometer dial is indicated at 74 and has a central hub 75 which fits over the member 72 and rests against the top of the flange 73. Beneath the flange 73 there is a split ring 76 which lies partly in a groove formed in the nut 60 near the upper end thereof, being rotatable on the nut. The parts are held together by means of screws such as 77 and 78 which pass through holes in the hub 75 and flange 73 and are threaded into the ring 76. Summing up the foregoing, it will be seen that the hand wheel 70 and the micrometer dial 75 are rigidly connected by means of the tubular member 72 and that these parts are rotatably mounted on the nut 60 (and thereby on the bearing member 20) by means of the split ring 76. This ring may be made in two overlapping sections so that it can be assembled in the groove in the nut 60.

The driving connection between the hand wheel and the micrometer screw 61 comprises two keys 80 and 81, shown in dotted lines in Fig. 2. The key 80 is also seen in Fig. 6. These keys are fixed in slots or keyways in the tubular member 72 and are slideable in keyways such as 82 in the micrometer screw 61. As the parts are shown in Fig. 6, the keys extend downward about half way into the keyways 82. Rotation of the hand wheel rotates the micrometer screw 61 in the nut 60 and raises or lowers the bearing member 20 on the column 18, depending on the direction of rotation, the keys 80 and 81 sliding in the keyways 82 during such movement. In its lowermost position the lower end of the bearing member engages the shoulder 88, Fig. 1, on the column 18. No stop is necessary to limit the upward movement of the bearing member. It may

be noted, however, that the keys 80 and 81 will leave the keyways 82 in the micrometer screw before the screw can be turned downward clear through the nut, which makes further rotation of the hand wheel in this direction ineffective and accordingly limits the distance through which the bearing member may be raised by rotation of the handwheel.

It may appear that rotation of the hand wheel would have a tendency to rotate the bearing member 20 and all associated parts about the column 18, the entire assembly being supported on the thrust bearing 65. It is indeed possible to accomplish this by a very careful and gradual application of force to the hand wheel. In the normal operation of the hand wheel, however, the hand wheel rotates relative to the bearing member and turns the micrometer screw 61 in nut 60 as described, due partly to the friction between the bearing member 20 and column 18 and partly to the great inertia of the bearing member and the heavy parts supported thereon. When the bearing member assembly is rotated in the course of the operation of the machine, by means of handle 30, for example, the entire assembly including the hand wheel and micrometer dial rotates as a unit, on the thrust bearing 65.

The plate 84 extends over the motor 50 and housing 31 and is attached to the top of the bearing members 20 by means of countersunk screws. It will be appreciated that since the plate 62 is circular there is ample room at the four corners of the bearing member for these screws. The plate 84 has openings therein for the motor shaft, the micrometer screw 61 and parts associated therewith, and the spindle 35. These openings are indicated in Fig. 6, except the opening for the motor shaft.

The belt guard 85 is shown in Figs. 1 and 2. This guard encloses the belts 55 and 56 and rests on the plate 84 to which it is secured by screws such as 86, Fig. 6. The guard is notched in front and rear for the micrometer dial 74, which extends outside the guard, and has an opening at the top for the tubular member 72 which supports the hand wheel 70 above the guard. The threaded nipple 87 is mounted on the guard as shown in Fig. 6 and is part of the circulating system for supplying coolant to the hollow spindle 35 which carries the grinding wheel 44.

The micrometer dial 74 is calibrated on its periphery and cooperates with an index member 88 which is mounted on the guard 85. This index member and part of the dial are shown on an enlarged scale in Fig. 8. The scale divisions on the dial are properly related to the pitch of the micrometer screw 61. The pitch of the screw may be 20 threads to the inch, for example, so that one complete rotation of the hand wheel will raise or lower the bearing member assembly $\frac{1}{20}$ or .050 of an inch. The micrometer dial may then have 50 scale divisions, each corresponding to a movement of .001 of an inch. The dial is relatively large and the scale divisions are far apart so that each division could be divided into 10 smaller divisions, each corresponding to .0001 of an inch. It is preferable, however, to place these finer scale divisions on the index member 88, as shown in Fig. 8.

It may be noted at this point that the driving connection between the hand wheel 70 and the micrometer screw 61 is substantially direct, the only relatively movable parts being the parts included in the sliding connection with the screw. The keys 80 and 81 are carefully fitted to the

keyways in the screw to eliminate play and the backlash as read on the micrometer dial does not exceed about .0002 of an inch.

The rotatable work support may be of any suitable construction, depending on the nature of the parts to be ground. It may have a chuck or collet, for example, for holding the parts. As shown herein, however, the work support is relatively simple, being adapted to support circular spacers or washers such as 90, and comprises a housing 91 and a flanged shaft 92 rotatably supported therein by means of bearings 93 and 94. The lower end of the housing 91 extends through an opening in the base 10 and a flange on the housing is received in an annular recess surrounding the opening, where it is secured by screws as indicated. The side wall of the sub-base 14 is cut away beneath the opening in the base 10 to provide room for the lower end of the housing 91 and shaft 92 and for the pulley 95 which is secured to the lower end of the shaft by the nut 96. As its upper end the shaft 92 has an accurately finished horizontal surface for supporting the work piece 90, which as previously mentioned may be a spacer or washer, which is to be ground to the required thickness. This spacer and other similar spacers to be ground may conveniently be provided with two small holes for receiving two pins which project upward from the finished surface at the end of the shaft. The reference character 97 indicates a guard which is provided to protect the bearing 93 against the entrance of dust and debris produced by the grinding operation.

The driving motor for the work support is indicated at 100 in Figs. 1 and 9. The motor is supported on the housing 101 which contains speed reducing gears for connecting the motor shaft with the output shaft 102. The housing 101 is secured to the wall of the subbase 14 in the proper position as shown in Fig. 1. A pulley 104 is mounted on shaft 102. The belt 103 is carried on pulleys 104 and 95 and serves to connect the shaft 102 with the shaft 92.

The mechanism for raising and lowering the bearing member 20 and associated parts on the column 18 during an automatic grinding cycle includes the tubular member 68, also referred to as the elevating sleeve. This sleeve is contained within the hollow column 18 and has bearings 45 above and below on the interior wall of the column in which it is slidably vertically. The sleeve 68 is closed at the lower end by the plate or disc 106.

The elevating lever 109 is pivoted on the bracket 107 which has a threaded extension by means of which it is fastened to the base 10. The lever 109 may be bifurcated or slotted at the ends for reception of the flattened end of bracket 107 at the right and the roller or follower 110 at the left, also the roller 108 which is engaged by the closure plate 106 of the elevating sleeve 68. The roller 108 is located only a short distance to the left of bracket 107, the ratio of the long arm of the lever to the short arm being about 3 to 1.

The driving motor for the elevating mechanism is indicated at 112. This motor is supported on the housing 113 which is attached to the wall of the subbase 14 as shown. The housing 113 contains speed reducing gears for connecting the shaft of motor 112 with the output shaft 114 to drive the latter at a slow speed, which may be, for example, about 2 rotations per minute. The 70 cam 116, shown on an enlarged scale in Fig. 3,

is mounted on the shaft 114 and cooperates with roller 108 for operating the lever 109. The housing 117, supported on the wall of subbase 14, contains a normally open switch which is operated by cam 118 by means of a lever mechanism 119 during each rotation of the shaft 114.

As shown in Fig. 2, there is a spring 120 which normally holds the edge of the apron 28 against the stop 121. In this position, the bearing member assembly including the grinding wheel 44 is rotated about 30 degrees in a counterclockwise direction from the position in which it is shown in Fig. 2. This leaves the rotatable work support 92 fully exposed and accessible to the operator.

When the operator rotates the bearing member assembly in a clockwise direction by means of the handle 39 to the position in which it is shown in Fig. 2, it becomes locked by a latching mechanism. This mechanism is partly enclosed in a housing 122 secured to the flanged upper rim of ring 12 and is so oriented that when the bearing member is in latched position the path of the grinding wheel 44 is directly above the center of the shaft 92 and the work piece 90 supported thereon.

Details of the latching mechanism are shown in Fig. 5. It comprises a frame 123 secured to the ring 12, a latch 124 which is pivotally mounted on the frame, and a catch 125 attached to the apron 28 and adapted to cooperate with the latch 124 as shown to hold the assembly in position against the pull of spring 120. It will be noted that the latch 124 is urged into operative engagement with the catch 125 by the spring 126. The solenoid 128 is mounted on frame 123 and is adapted, when energized, to rotate latch 124 on its pivot to release the catch 125. This permits the grinding wheel assembly to be rotated by the spring 120 until its movement is arrested by the stop 121. When the solenoid 128 is deenergized, the ensuing rotation of the latch 124 by the spring 126 causes it to engage the operating member 129 of a normally closed switch 127 and open it. These operations will be explained more fully in connection with Fig. 7.

Referring now to Fig. 7, the reference character S indicates the main switch, through which three-phase alternating current is supplied to the conductors 141, 142 and 143 and thence to the motors 50, 100 and 112 under control of relays 144 and 145. These relays may be of any suitable construction, adapted to operate on alternating current, and are shown in conventional manner. The switches S1 and S2 are stop and start switches, respectively, and are also shown conventionally. Other parts shown in the circuit drawing have already been described.

It will be understood that the switches S1 and S2 may be mounted in suitable manner on the base of the machine, where they will be convenient to the operator. These switches and the wiring are not shown in the mechanical drawings. Fig. 1 does, however, show the conduits 150 and 151 for the conductors 155 which supply current to the motor 50. The conduit 150 is supported on the base 18 by a clamp 152 and on the flanged ring 12 by the bracket 153. The conduit 151 is supported on the plate 84 by a holding device 154. The upper ends of the conduits are above the center of column 18 and are spaced apart for a short distance, where the conductors 155 are unconfined. These conductors are flexible and the arrangement thus provides for about

75 grinding operations by closing the main switch

360 degree rotation of the grinding wheel assembly about the column 18. It will be appreciated, however, that the machine is inherently adapted for continuous rotation of the grinding wheel assembly about column 18.

The operation of the machine will now be explained, it being assumed for this purpose that the machine is to be used for grinding finished surfaces on spacers such as 90. Some preliminary adjustments which have to be made on setting up the machine will first be explained.

The cam 118 is designed in accordance with the particular grinding job to be performed, although of course a given cam may be used on different jobs if conditions permit. Several cams may be provided and are readily interchangeable. In the present case it may be assumed that the maximum amount of material which has to be removed on any spacer to reduce it to the required thickness is about .030 of an inch. The total lift of the grinding wheel should then be about .050 of an inch, in order to afford the necessary clearance between the work and the wheel as the latter is moved to grinding position. The total rise on the cam should be sufficient to produce the indicated lift of the grinding wheel plus an additional amount which is necessary in order to insure that during the spark out period the thrust bearing 85 will be supported on the shoulder 87 in column 18 rather than on the cam. It is preferable to allow about .005 of an inch clearance between the roller 108 and the plate 106 when the cam follower 110 is resting on the spark out section of the cam in order to insure that the above condition will obtain.

Since the roller 108 is located in the subbase where it is not very accessible the clearance may be measured by means of a thickness gauge inserted between the cam and the follower 110, making due allowance for the difference in the length of the lever arms of lever 109. If the cam is not in the proper position, the machine is started in the manner more fully described hereinafter and is stopped when the spark out section of the cam comes into engagement with the follower. The clearance is then measured and if any adjustment is required it is accomplished by raising or lowering the housing 113 on the subbase 14. The housing is secured to the subbase by cap screws which extend through slots in the flanges or feet of the housing which rest against the subbase so that the adjustment can be made as described.

The grinding wheel is adjusted relative to the work with the cam follower 110 resting on the dwell section of the cam, as it is shown in Fig. 1. With the parts in this position, and with a work piece or spacer 90 on the work support 92, the grinding wheel is lowered by means of the hand wheel 78 until it clears the top of the spacer 90 by about .020 of an inch. The grinding wheel assembly should be in latched position above the work support while the adjustment is being made and after it is completed the latch 124 can be released by hand to permit restoration of the grinding wheel to normal position with the edge of apron 28 against the stop 121. It will be understood that the adjustment of the grinding wheel as well as the adjustment of the cam is made with the main switch open and the motors inactive, the power being applied only to rotate the cam to the proper position when necessary.

The machine being ready, the operator starts

S again, after which he operates the start switch S2 momentarily and then rotates the grinding wheel assembly to grinding position by means of the handle 30, where it is held by the latch 124. The closure of the main switch supplies current to the conductors 141, 142 and 143. The operation of the start switch closes a circuit for relay 145 in an obvious manner, bridging the relay across the conductors 141 and 143. Upon energizing, relay 145 establishes a holding circuit for itself at contact 146 and at its three upper contacts it extends the three conductors 141, 142 and 143 through to the motor 50, which starts to run and rotate the grinding wheel 44.

When the catch 125 becomes locked by the latch 124, the latter is rotated sufficiently to permit the switch 127 to close, thereby establishing a circuit for relay 144. Upon energizing, relay 144 closes the three conductors 141, 142 and 143 through to the motors 100 and 112 and these motors begin to run. Motor 100 rotates the shaft or work support 92 and the work piece, spacer 90, which is supported thereon. Motor 112 rotates the shaft 114 and the cams 115 and 116.

In response to rotation of the cam 116, the cam follower 110 leaves the dwell section of the cam and passes on to the rapid feed section, causing the grinding wheel to be quickly lowered into engagement with the work piece 90. This is accomplished by the lever 109 and the elevating sleeve 68. Grinding now begins and continues as the grinding wheel is gradually lowered by co-operation of the cam follower with the slow feed section of the cam. Shortly before the end of this section of the cam is reached the ring 66 supporting the thrust bearing 65 comes to rest on the shoulder 67, which prevents further lowering of the grinding wheel. The cam rotates freely during the spark out period, therefore, while the grinding wheel cooperates with the rotating work support to produce a finished surface on the work piece 90.

At the end of the spark out period, the cam follower comes into engagement with the wheel rise section of the cam, causing the grinding wheel to be raised off the work piece by means of lever 109 and the elevating sleeve 68. When the cam follower reaches the dwell section of the cam 116, the cam 115 closes the switch 117, thereby closing a circuit for the solenoid 128. Upon energizing, solenoid 128 rotates the latch 124 to release the catch 125, whereupon the grinding wheel assembly is rotated on the column 18 by the spring 126 until its movement is arrested by the stop 121. The continued rotation of cam 115 now permits the switch 117 to open, deenergizing the solenoid 128. This takes place while the cam follower 110 is still in engagement with the dwell section of cam 116. Upon deenergization of solenoid 128, the spring 126 rotates the latch 124 to open the switch 127, whereupon the relay 144 deenergizes and stops the motors 100 and 112. This completes the grinding cycle.

The operator may now remove the spacer 90 from the work support and measure it with a micrometer to determine if its thickness is correct, or within the tolerance limits assigned. Being the first piece ground, it may not be exactly right, so that adjustment of the grinding wheel is necessary. This can be done very accurately by means of the hand wheel 70 while reading the amount by which the grinding wheel is raised or lowered on the micrometer dial 74 and the associated index member 88.

Another spacer such as 90 may now be placed

in position on the work support 92, after which the grinding wheel assembly is again rotated to grinding position by the handle 30. The grinding wheel becomes latched in this position as before and the operation of the latch 124 closes the switch 127 to energize relay 144 and start the next grinding cycle.

It will be noted that the work supporting surface on shaft 92 and the shoulder 67 on column 18 are fixed as regards their relative elevation, so that the only variable which can affect the thickness of the finished spacers is the gradual wearing away of the grinding wheel. The operator takes this factor into consideration by measuring the finished spacers from time to time as they are removed from the work support and by lowering the grinding wheel when necessary.

During grinding operations as described the motor 50 continues to run. If it should become necessary to stop the motor for any reason, this can be done by operating the stop switch S1 to open the holding circuit of relay 145. In an emergency the stop switch may also be used during a grinding cycle to stop the other motors.

The grinding machine is adapted for use as a hand operated machine for grinding work pieces supported on the magnetic chuck 17, or on other work supports arranged on the surface 16 of the base 10. In order to prepare the machine for this type of grinding operation without preventing the relatively quick resumption of the grinding operations such as previously described, the machine may be stopped with the cam follower 110 on the spark out section of the cam 116 so that the thrust bearing 65 is supported on the shoulder 67. The spring 120 is then unhooked at the apron 28 and the latch mechanism 122 is unfastened and moved radially outward where it will not interfere with the catch 127 and the apron 28. The frame 123 of the latching mechanism may conveniently be provided with an extension 130 which can be screwed to the flanged rim 12 to hold the latching mechanism in this position.

The foregoing preparations having been made, the grinding wheel 44 may be rotated into position above the chuck 17. The motor 50 is started as previously explained, but the motors 100 and 112 remain inactive because the circuit of relay 144 is held open at the latching mechanism, now in inoperative position. Grinding is accomplished by lowering the grinding wheel on to the work and oscillating the wheel over the work in a manner which will be understood without further explanation.

The invention having been described that which is believed to be new and for which the protection of Letters Patent is desired will be pointed out in the appended claims:

1. In a grinding machine, a base, a vertical column extending upward from said base, a bearing member rotatable and slidable on said column, a grinding wheel and a driving motor therefor mounted on said bearing member, a nut disposed coaxially with said column and fixed to said bearing member, a micrometer screw threaded in said nut, a thrust bearing supporting said screw on said column, a hand wheel rotatably mounted on said bearing member, said hand wheel being disposed in a horizontal plane with its center on the axis of said column, and a driving connection between said hand wheel and said screw, whereby rotation of said hand wheel rotates said screw in said nut to raise or lower said bearing member on said column.

2. In a grinding machine, a base, a vertical column extending upward from said base, a bearing member rotatable and slidable on said column, a grinding wheel and a driving motor therefor mounted on said bearing member, a nut disposed coaxially with said column and fixed to said bearing member, a micrometer screw threaded in said nut, a thrust bearing supporting said screw on said column, a hand wheel disposed coaxially with said column and rotatably supported on said bearing member said hand wheel being of relatively large diameter and accessible from any point around the machine, a calibrated dial also disposed coaxially with said column and fixed to said hand wheel, means responsive to rotation of said hand wheel and dial relative to said bearing member for rotating said screw in said nut to raise and lower said bearing member on said column, and an index member fixed relative to said bearing member and cooperating with said dial to indicate thereon the extent of such movement.

3. In a grinding machine, a base, a vertical column extending upward from said base, a bearing member rotatable and slidable on said column, a grinding wheel and a driving motor therefor mounted on said bearing member, a nut disposed coaxially with said column and fixed to said bearing member, a micrometer screw threaded in said nut, a thrust bearing supporting said screw, nut, and bearing member on said column, means rotatably mounted on said bearing member for rotating said screw in said nut to raise and lower said bearing member on said column, said means having a connection with said screw, a circular dial having scale divisions extending around its periphery, said rotating means supporting said dial coaxially with said column for rotation with said screw, and an index member fixed during such rotation and cooperating with the dial to indicate thereon the extent of the movement of the bearing member.

4. In a grinding machine, a base, a vertical column extending upward from said base, a bearing member rotatable and slidable on said column, a grinding wheel and a driving motor therefor mounted on said bearing member, a nut disposed coaxially with said column and fixed to said bearing member, a micrometer screw threaded in said nut, a thrust bearing supporting said screw on said column, a tubular member partly enclosing said screw and rotatably mounted on said bearing member, an operating device and a circular calibrated dial supported on said tubular member, said dial being coaxial with said screw and disposed in a horizontal plane, means responsive to rotation of said tubular member by said operating device for rotating said screw in said nut to raise and lower said bearing member on said column, and an index member relative to which the dial rotates during rotation of the screw, said index member cooperating with the dial to show thereon the extent of movement of the bearing member on said column.

5. In a grinding machine, a base, a vertical column extending upward from said base, a bearing member rotatable and slidable on said column, a grinding wheel and a driving motor therefor mounted on said bearing member, a nut disposed coaxially with said column and fixed to said bearing member, a micrometer screw threaded in said nut, a thrust bearing supporting said screw on said column, means for rotating said bearing member and the grinding wheel mounted thereon about said column as an axis to bring the wheel

into operative relation to work supported on said base, said nut and screw rotating with said bearing member, a hand wheel supported on said bearing member and partaking in such rotation 5 thereof, the supporting means for said hand wheel providing for rotation thereof on the axis of said column independent of the bearing member, and means responsive to such independent rotation for rotating said screw in said nut to raise and lower said bearing member on said column.

6. In a grinding machine, a horizontal base, a column extending vertically upward from said base, an assembly comprising a bearing member rotatable and slidable on said column and having mounted thereon a grinding wheel and driving motor therefor, and means for raising and lowering said assembly on said column comprising a support on said column and elements including a thrust bearing, a lead screw and a nut threaded thereon disposed in serial relation on the axis of said column, one of said elements resting on said support and another of said elements having a connection with said bearing member, an operating member having a longitudinally sliding but non-rotative connection with said lead screw, and means for rotating said operating member to rotate said lead screw in said nut to raise and lower said bearing member on said column as set forth.

7. In a grinding machine, a base, a vertical column extending upward from said base, a bearing member rotatably and slidably mounted on said column, a grinding wheel assembly including a grinding wheel and mounted on said bearing member for movement in a circular path above said base, a motor mounted on said bearing member for driving said grinding wheel, a work support mounted on said base in the said path, means having a connection to said assembly and tending to rotate the same to position said grinding wheel at a point angularly spaced from said work support, latching mechanism operating to hold said grinding wheel assembly when the same is rotated about said column to a position above said work support, and means responsive to operation of said latching mechanism to automatically lower said bearing member on said column to feed the grinding wheel into operative relation to a work piece on said work support.

8. In a grinding machine, a base, a vertical column extending upward from said base, a bearing member rotatably and slidably mounted on said column, a grinding wheel assembly including a grinding wheel and mounted on said bearing member for movement in a circular path above said base, a motor mounted on said bearing member for driving said grinding wheel, a work support mounted on said base at a point in the said path which is angularly spaced from said grinding wheel, means for rotating said work support, and means responsive to rotation of said grinding wheel assembly about said column to a position above said work support for starting the rotation of said work support and for lowering said bearing member to feed the grinding wheel into operative relation to a work piece on said support said last means including electric motors and circuits therefor and a switch actuated by said assembly on arrival at said position to close said circuits.

9. In a grinding machine, a base, a vertical column extending upward from said base, a bearing member rotatably and slidably mounted on said column, a grinding wheel assembly including a grinding wheel and mounted on said bearing

member for movement in a circular path above said base, a motor mounted on said bearing member for driving said grinding wheel, a work support mounted on said base in the said path, latching mechanism holding said assembly in a position above said work support when the assembly is rotated to such position, means responsive to such rotation for automatically lowering said bearing member to feed the grinding wheel on to a work piece on said support, means operated in timed relation to the grinding wheel feed for releasing said latching mechanism, and means effective upon such release for rotating said assembly about said column to a position out of alignment with said work support.

10. In a grinding machine, a base, a vertical column extending upward from said base, a bearing member rotatably and slidably mounted on said column, a grinding wheel assembly including a grinding wheel and mounted on said bearing member for movement in a circular path above said base, a motor mounted on said bearing member for driving said grinding wheel, a work support mounted on said base in the said path, and mechanism for sliding said bearing member on said column to move the grinding wheel in and out of operative relation to a work piece on said support, said mechanism including a vertical member slidably mounted in bearings inside said column and extending beneath said base, means including a thrust bearing supporting said bearing member on said vertical member, and mechanism beneath said base engaging said vertical member for operating said vertical member for the purpose set forth.

11. In a grinding machine, a base, a vertical column extending upward from said base, a bearing member surrounding and rotatable and slidably on said column, a grinding wheel assembly including a grinding wheel and mounted on said bearing member for movement in a circular path above said base, a motor mounted on said bearing member for driving said grinding wheel, a work support mounted on said base in the said path, a support carrying the weight of said bearing member, means acting against said support and having a connection to said bearing member for adjusting the elevation of said bearing member relative to its said support by sliding it on said column to thereby adjust said grinding wheel relative to a work piece on said work support, mechanism connected to said bearing member through said adjusting means for holding said bearing member off its said support during movement of the grinding wheel to a position above said work support, and means for operating said mechanism to lower said bearing member on to its said support to effect a desired grinding operation on said work piece.

12. In a grinding machine, a base, a vertical column extending upward from said base, a grinding wheel assembly comprising a grinding wheel and a driving motor therefor, said assembly having a bearing on said column providing for rotative and sliding movement of the assembly on said column, a work support on said base in the path of said grinding wheel when the same is rotated about said column, mechanism for raising and lowering said assembly on said column, means responsive to the grinding wheel being positioned above said work support for operating said mechanism to lower said assembly on said column and to raise the same after the lapse of a predetermined time interval to cause the grinding wheel to remove material from a

work piece on said support, said means including a motor for driving said mechanism and motor starting means operated by a part of said assembly when said grinding wheel arrives in position above said work support, and means interposed between said mechanism and said assembly for preadjusting the elevation of said assembly relative to said mechanism in accordance with the depth of material to be removed.

13. In a grinding machine, a base, a vertical column extending upward from said base, a grinding wheel assembly comprising a grinding wheel and a driving motor therefor, said assembly having a bearing on said column providing for rotative and sliding movement of the assembly on said column, a work support on said base in the path of said grinding wheel when the same is rotated about said column, mechanism including a rotatable cam holding said assembly in an elevated position to permit the grinding wheel to be rotated about said column to a position above said work support, means responsive to such rotation for rotating said cam to lower said assembly on said column to bring the grinding wheel into engagement with a work piece on said work support and grind the same, and means independent of said cam supporting said assembly during the final stage of the grinding operation.

14. In a grinding machine, a base, a vertical column extending upward from said base, a grinding wheel assembly comprising a grinding wheel and a driving motor therefor, said assembly having a bearing on said column providing for rotative and sliding movement of the assembly on said column, a work support on said base in the path of said grinding wheel when the same is rotated about said column, automatic feed mechanism having a connection to said assembly for raising and lowering said assembly on said column, said mechanism normally holding said assembly in raised position to permit said grinding wheel to be rotated about said column to a position above said work support, means including a device actuated by said rotation for operating said feed mechanism through a cycle of predetermined duration to perform a grinding operation on a work piece on said work support by lowering and then raising said assembly, and means independent of said feed mechanism supporting said grinding wheel at a fixed distance above said work piece during the final stage of said grinding operation.

15. A grinding machine as claimed in claim 14, characterized by the provision of a cam forming part of said feed mechanism, said cam having a dwell section for supporting the assembly during rotation thereof to position above the work support, a rapid feed section to start the grinding operation, and a slow feed section to continue the grinding operation up to the final stage.

16. In a grinding machine, a base, a vertical column extending upward from said base, a grinding wheel assembly comprising a grinding wheel and a driving motor therefor, said assembly having a bearing on said column providing for rotative and sliding movement of the assembly on said column, adjustable means supporting the weight of said assembly to control said sliding movement, a work support on said base in the path of said grinding wheel when the same is rotated about said column, spring means normally maintaining said grinding wheel assembly in an inoperative position relative to said work support, a stop determining said position, means

locking the grinding wheel assembly in operative position above said work support when rotated to such operative position, and automatic control means connected with and adapted to operate said adjustable supporting means for lowering and raising the grinding wheel to perform a grinding operation on a work piece on said support, said control means including means for releasing said locking means upon the completion of said grinding operation.

17. In a grinding machine, a base, a vertical column extending upward from said base, a bearing member rotatably and slidably mounted on said column, a grinding wheel mounted on said bearing member for rotation on a vertical axis spaced from said column, said wheel being movable in a circular path above said base by rotation of said bearing member about said column, means sustaining the weight of said bearing member during rotation thereof about said column, said means comprising a nut disposed coaxially with said column and fixed to said bearing member, a micrometer screw threaded in said nut and a thrust bearing disposed between said screw and a support connected to said base, an operating device for rotating said screw in said nut to raise and lower said bearing member on said column, said device being mounted on and partaking in the movements of said bearing member, the mounting means for said device comprising interengaging bearing elements coaxial with and surrounding said screw and providing for rotation of said device relative to said bearing member, and a connection between said device and said screw which permits the device to move axially of said screw while rotating the same.

18. In a grinding machine, a base, a vertical column extending upward from said base, a bearing member rotatably and slidably mounted on said column, a grinding wheel assembly including a grinding wheel and mounted on said bearing member for movement in a circular path above said base, a motor mounted on said bearing member for driving said grinding wheel, means tending to maintain said assembly at a normal position in said path, a work support mounted on said base at a different position in said path, means including a second motor for lowering said bearing member on said column, a third motor for rotating said work support, electrical circuits for said motors, means for closing the circuit of said first motor, and switching means actuated responsive to rotation of said assembly about said column from said normal position to a position above said work support to close the circuits of the said second and third motors, whereby the work support is rotated and the grinding wheel is fed on to a work piece on said support.

19. In a grinding machine, a base, a vertical column extending upward from said base, a bearing member rotatably and slidably mounted on said column, a grinding wheel assembly including a grinding wheel and mounted on said bearing member for movement in a circular path above said base, a motor mounted on said bearing member and having a driving connection to said grinding wheel, means having a connection to said assembly and tending to rotate the grinding wheel to a normal position in said path, latching mechanism operative to hold said assembly when the same is rotated to a position above a work piece supported on said base, automatic mechanism operating to cause said grinding wheel to perform a predetermined grinding operation on said work piece by lowering and raising said bear-

ing member on said column, and means operating to release said latching mechanism upon the completion of said grinding operation.

20. In a grinding machine, a base, a vertical column extending upward from said base, a bearing member rotatably and slidably mounted on said column, a grinding wheel assembly including a grinding wheel and mounted on said bearing member for movement in a circular path above said base, a motor mounted on said bearing member and having a driving connection to said grinding wheel, means having a connection to said assembly and tending to rotate the grinding wheel to a normal position in said path, latching mechanism operative to hold said assembly when the same is rotated to a position above a work piece supported on said base, and mechanism for sliding said bearing member on said column to move said grinding wheel in and out of operative relation to said work piece, said mechanism including a lever pivoted on said base, a cam operatively engaging one arm of said lever, and a connection between the other arm of said lever and said bearing member.

21. A grinding machine as claimed in claim 20, wherein the connection between the lever arm and bearing member includes mechanism operative to adjust the elevation of the grinding wheel prior to starting the grinding operation.

22. In a grinding machine, a base, a vertical column extending upward from said base and having a finished external bearing surface, a bearing member surrounding said column and rotatably and slidably engaging said bearing surface, a grinding wheel and a driving motor therefor mounted on said bearing member, means comprising a thrust bearing, a micrometer screw coaxial with said column and a nut threaded on said screw supporting said bearing member, said nut being fixed to said bearing member, an adjusting device, bearing means supporting said device on said bearing member for rotation therewith when the bearing member is rotated on said thrust bearing, said bearing means providing for rotation of said device independent of said bearing member, and a driving connection between said device and screw to rotate the screw in said nut to raise and lower the bearing member on said column.

23. In a grinding machine, a base, a vertical column extending upward from said base, a bearing member rotatably and slidably mounted on said column, a grinding wheel assembly including a grinding wheel and mounted on said bearing member for movement in a circular path above said base, a motor mounted on said bearing member for driving said grinding wheel, a work support mounted on said base in the said path, means including a rotatable cam for lowering and raising said bearing member on said column, said means also including a device operated by said cam and having an operative connection to said bearing member, a second motor for rotating said cam, a circuit including said second motor and a switch actuated to complete said circuit by movement of said grinding wheel assembly to a position above said work support, whereby said grinding wheel is fed on to a work piece on said support and then lifted therefrom by rotation of said cam, and means operated by said second motor and effective upon a complete rotation of said cam to open said circuit to stop said second motor.

ALFRED J. BOWEN.
